Primary Examiner — T. Chase Nelson(74) Attorney, Agent, or Firm — Banner & Witcoff, Ltd.(57) CLAIM

The ornamental design for a shoe outsole, as shown and described.

DESCRIPTION

FIG. 1 is a front perspective view of a shoe outsole showing my new design;

FIG. 2 is a plan view thereof;

FIG. 3 is a rear perspective view thereof;

FIG. 4 is an enlarged view of FIG. 1 with disclaimed features removed for clarity;

FIG. 5 is an enlarged view of FIG. 2 with disclaimed features removed for clarity; and,

FIG. 6 is an enlarged view of FIG. 3 with disclaimed features removed for clarity.

The remainder of the shoe outsole depicted in part in broken lines is for environmental purposes only and forms no part of the claimed design.

1 Claim, 6 Drawing Sheets(56)
